KITCHEN WALL CABINET

Leroy J. Koch, New Port Richey, Fla.

Application June 26, 1940, Serial No. 342,557

2 Claims. (Cl. 126—299)

The invention aims to provide a new and improved wall cabinet to be mounted in what is ordinarily waste space over a kitchen stove, portions of said cabinet being so constructed to act as a ventilator for directing ascending hot air and fumes to an escape flue.

With the foregoing in view, the invention resides in the novel subject matter hereinafter described and claimed, description being accomplished by reference to the accompanying drawing.

Figure 1 is a perspective view showing the cabinet mounted over a stove which may be considered as a gas, electric, oil or solid fuel stove.

Figure 2 is a vertical sectional view substantially on line 2—2 of Fig. 1, the stove being in elevation.

Figure 3 is a detail vertical section on line 3—3 of Fig. 2.

In the drawing above briefly described, the numerals 5 denote two parallel vertical side walls secured at their upper ends to a horizontal top 6, said side walls and top being of uniform width. A vertical back wall 7 is spaced forwardly from the rear edges of the side walls 5 and extends from one of said side walls to the other. The back wall 7 also extends upwardly to the top 6, but the lower end of said back wall 7 is spaced upwardly from the lower ends 8 of the side walls 5. A bottom 9 declines forwardly from the lower end of the back wall 7 substantially to the lower front corners 10 of the side walls 5.

The cabinet space in front of the back wall 7 is of course accessible from the front of the cabinet, although hinged doors could of course be provided instead of having the cabinet front entirely open as herein shown. In the present disclosure, this cabinet space is provided with vertically spaced shelves 11 and 11^a, all of which extend between the side walls 5. The shelves 11 extend rearwardly to the back wall 7 and the shelves 11^a extend rearwardly to the forwardly declined bottom 9. The part denoted at 12 is merely a finishing strip at the lower front portion of the cabinet and similar strips could of course be provided elsewhere if desired.

When the cabinet is mounted against a wall 13 over a stove 14, the space 15 behind the back wall 7 constitutes a hot air and fume escape passage, which passage has an opening 16 at its upper end to communicate with an appropriate vent flue 17. The lower end portions of the side walls 5 and the cabinet bottom 9 cooperate in forming a hood 18 which receives the ascending fumes and hot air and directs them into the

escape passage 15. The bottom 9 and the back wall 7 of course become heated, and as the shelves 11 and 11^a are secured to these parts, said shelves also become heated to quite an extent. Therefore, the cabinet may be effectively used to keep food warm before serving, and this is particularly true when suitable doors (not shown) are employed at the cabinet front.

To aid in discharging the ascending fumes and hot air, a motor-driven fan 19 may be provided if desired. I have shown such a fan mounted on an appropriate bracket 20 and accessible through an opening 21 in the upper end of the back wall 7, said opening being normally closed by a suitable plate 22. At opposite sides of the fan, I have disclosed two upwardly converging baffles 23 in the passage 15 to aid in directing the ascending currents to the flue 17.

In order to prevent any entrance of cold air through the flue 17 and the passage 15, during cold weather, an appropriate damper 24 may be employed to close said passage. I have shown an operating knob 25 for this damper.

In the present disclosure of the invention, another wall 26 is disposed behind the back wall 7 and is secured to the top 6 and the side walls 5, but said wall 26 is not absolutely essential, as its equivalent would be provided simply by the kitchen wall 13 when mounting the cabinet.

From the foregoing taken in connection with the accompanying drawing, it will be seen that novel and advantageous provision has been made for carrying out the object of the invention. It is to be understood, however, that within the scope of the invention as claimed, minor variations may be made.

I claim:

1. A kitchen wall cabinet comprising parallel vertical side walls extending inwardly from a wall of the kitchen and spaced above a stove, a top also extending inwardly from said kitchen wall and secured to the upper ends of said side walls, a back wall spaced forwardly from the rear edges of said side walls and thus spaced inwardly from said kitchen wall, said back wall extending from one of said side walls to the other and being secured thereto, said back wall extending upwardly to and being secured to said top and having its lower end spaced above the lower ends of said side walls, the space behind said back wall being unobstructed from one of said side walls to the other and constituting a ventilation passage extending throughout the width of the cabinet, a cabinet bottom secured to said lower end of said back wall and declined forwardly therefrom sub-

stantially to the lower front corners of said side walls, the ends of said forwardly declined cabinet bottom being secured to said side walls, the lower end of the cabinet below said forwardly declined cabinet bottom being entirely open and spaced in its entirety above the stove, whereby said forwardly declined bottom and the lower ends of said side walls may cooperate in directing ascending hot air into said ventilation passage, shelves secured to said back wall to absorb heat therefrom, and a hot air outlet from the upper end of the aforesaid ventilation passage.

2. A kitchen wall cabinet comprising parallel vertical side walls extending inwardly from a wall of the kitchen and spaced above a stove, a top also extending inwardly from said kitchen wall and secured to the upper ends of said side walls, a back wall spaced forwardly from the rear edges of said side walls and thus spaced inwardly from said kitchen wall, said back wall extending from one of said side walls to the other and being secured thereto, said back wall extending upwardly to and being secured to said top

5 and having its lower end spaced above the lower ends of said side walls, the space behind said back wall being unobstructed from one of said side walls to the other and constituting a ventilation passage extending throughout the width of the cabinet, a cabinet bottom secured to said lower end of said back wall and declined forwardly therefrom substantially to the lower front corners of said side walls, the ends of said forwardly declined cabinet bottom being secured to said side walls, shelves secured to and extending forwardly from both said back wall and said forwardly declined cabinet bottom to absorb heat therefrom, the lower end of the cabinet below said forwardly declined cabinet bottom being open and spaced in its entirety above the stove, whereby said forwardly declined cabinet bottom and the lower ends of said side walls may direct ascending hot air into said ventilation passage for kitchen ventilation and shelf heating, and a hot air outlet from the upper end of said ventilation passage.
